UNITED STATES PATENT OFFICE.

FRANK L. BUFF, OF WICHITA, KANSAS.

TRAFFIC-SIGNAL.

1,391,240.

Specification of Letters Patent. Patented Sept. 20, 1921.

Application filed December 12, 1919. Serial No. 344,376.

To all whom it may concern:

Be it known that I, FRANK L. BUFF, a citizen of the United States, residing at Wichita, in the county of Sedgwick and State of Kansas, have invented a new and useful Traffic-Signal, of which the following is a specification.

This invention relates to traffic signals for use on vehicles and primarily designed 10 for attachment to motor vehicles whereby the direction in which the vehicle is about to move can be plainly indicated to the occupant of a following vehicle or to a person in the path of said vehicle.

15 Another object is to provide a simple and efficient device which can be attached readily to a vehicle without requiring the services of a skilled mechanic.

A still further object is to provide a device which is easy and convenient to operate 20 and which can be actuated so as to indicate a right or left turn, a stop, or a reverse or backing movement.

With the foregoing and other objects in 25 view which will appear as the description proceeds, the invention consists of certain novel details of construction and combinations of parts which will be hereinafter more fully described and pointed out in the 30 claim, it being understood that various changes may be made in the construction and arrangement of the parts without departing from the spirit or sacrificing any of the advantages of the invention as set 35 forth in the appended claim.

In the accompanying drawings the preferred form of the invention has been shown.

In said drawings—

40 Figure 1 is a view partly in elevation and partly in section showing the device in position on a wind shield.

Fig. 2 is an elevation of the device showing the inner side thereof.

45 Fig. 3 is an enlarged transverse section through the device in position on a wind shield.

Fig. 4 is an elevation of the complete device on a reduced scale and showing the different positions of the signal arm.

Referring to the figures by characters of reference, 1 designates the main plate of the device, the same being provided at one side with a rounded flange 2 constituting a 55 jaw. A clamping plate 3 is connected to the plate 1 by a bolt 4 and has one side offset

to form a rounded jaw 5 while its opposite side is turned inwardly and bears against the plate 1, as shown at 6. The two jaws 2 and 5 are adapted to receive between them a 60 supporting structure 7 which, in the present instance, is one side of the frame of a windshield. By tightening the nut 8 on the bolt 4 the jaws 5 and 2 will be caused to tightly grip the support 7. 65

A bearing pin 9 is mounted in the plate 1 and is provided with a spring washer 10. Journaled on this pin between the plate 1 and the washer 10 is a gear 11 which meshes with another gear 12 journaled on a pin 13. 70 This pin extends from the plate 1 and is engaged by a spring washer 14 on the pin. An arm 15 is secured to the gear 12 by means of one or more rivets 16 and is preferably shaped to simulate the arm of a person, there being the representation of a hand at the free end thereof, as shown at 17. A spring strip 18 is secured to the plate 1 preferably by the pin 13 and bears against a ball 19 loosely mounted in an opening 20 80 in the plate 1. This ball is adapted to be seated in any one of a series of notches 21 formed in the gear 12 so that when the said gear is rotated to bring the arm 15 to any one of a series of positions, the ball will become seated in one of the notches and hold the arm in such position. 85

A housing plate 22 is mounted on one face of the plate 1 and has an opening 23 into which the plate 3 extends, as shown in 90 Fig. 3. This plate 22 extends over, under and to one side of the plate 1 and the gears thereon and close to the arm 15. Another housing plate is located at the other side of the arm 15, as shown at 24 and extends 95 close to the arm 15 and completes the housing of the gears. This plate 24 can be secured in any manner desired, as by means of one or more bolts 25 extending from the plate 1 above and below the gear 11. A 100 mirror 26 is secured to the plate 24 for the convenience of the driver of the vehicle.

Extending rearwardly from the inner side of the plate 1 is a bracket 27 on which is journaled a segmental gear 28 having a hand 105 lever 29 extending therefrom. Gear 28 meshes with the gear 11 and is provided on its exposed face with designating characters, as shown in Fig. 2. For example the gear may be provided with the letter "N", 110 designating the neutral or downwardly hanging position of the arm 15. A letter

"R" can be provided for indicating when the arm is in a downwardly inclined position to signal a turn to the right. A letter "S" may be provided for indicating 5 when the arm 15 is in a horizontal position to signal a stop. A letter "L" may be provided for indicating an upwardly inclined position of the arm 15 to signal a left turn, and the letter "B" may be provided for 10 indicating an upstanding vertical position to signal a backward or reverse movement of the vehicle. An index or pointer 30 is arranged on the bracket and by pulling the lever 29 so that the selected letter will register with this index the arm 15 will be brought to the position desired. The various positions of the arm 15 have been illustrated clearly in Fig. 4. It will be understood that the arm will be held in any one 15 20 of its positions by the seating of the spring pressed ball 19 in one of the notches.

Although the arm 15 as shown is a simulation of the arm of a person it is to be understood that it can be of any desired shape 25 to serve as a semaphore.

What is claimed is:—

The combination with a main plate having a jaw, of a clamping plate, a housing plate held to the main plate by the clamping plate, a housing plate secured to and spaced from the main plate, meshing gears carried by the main plate and between the housing plates, a bracket extending from the main plate, a controlling lever carried by the bracket, a gear movable with said lever and meshing with one of the gears in the housing, said lever being movable in a plane intersecting the plane of movement of the gears, an index on the bracket, and means movable with the lever and coöperating with 30 35 40 the index for designating the degree of rotation of the gears.

In testimony that I claim the foregoing as my own, I have hereto affixed my signature in the presence of two witnesses.

FRANK L. BUFF.
